UNITED STATES PATENT OFFICE.

GEORGE R. DEAN, OF CHICAGO, ILLINOIS; EMILY WASHBURN DEAN ADMINISTRATRIX
OF SAID GEORGE R. DEAN, DECEASED.

ROOF CONSTRUCTION.

Application filed May 23, 1919. Serial No. 299,108.

To all whom it may concern:

Be it known that I, GEORGE R. DEAN, a citizen of the United States, residing at Chicago, in the county of Cook and State of Illinois, have invented a certain new and useful Improvement in Roof Constructions, of which the following is a full, clear, concise, and exact description, reference being had to the accompanying drawings, forming a part of this specification.

My invention relates to roofs, and especially to tile or similar roofs.

The principal object of the invention is to provide a simple and practical construction of tile roof.

Another object of the invention is to reduce the amount of tile necessary for the roof and thereby reduce the weight of the roof and the expense of making the same.

Another object of the invention is to permit the changing of an ordinary shingle roof into a tile roof, and to accomplish this with very little trouble and expense.

In the accompanying drawings Fig. 1 is a perspective view of a section of roof embodying my present invention;

Fig. 2 is a cross section of a shingle roof with my improved tile construction applied thereto.

Referring to the drawings and especially to Fig. 1, I show a roof having the usual roof timbers 1. On these are mounted longitudinally extending strips 2—2 preferably made of wood. These strips 2—2 preferably overlap one another slightly and are desirably rabbeted at 3 where they overlap one another. Upon these cross strips 2—2 are mounted layers or strips 4 of felt or similar material. Each one of these strips 4 is mounted upon

the upper surface of one of the strips 2 and then extends downwardly and lies upon the upper surface of the strip 4 next below it. Tiles 5 are mounted upon the strips 4. Each tile 5 is mounted upon the portion of a layer

4 which overlays another layer 4, each layer 4 being substantially the width of two tiles. Thus under each tile there are two layers 4 of felt or similar material. The tiles 5 preferably overlap each other a small extent.

Nails 6 are passed through the upper edges of the tiles 5 and also through the felt 4 and into the cross strips 2 so as to hold the tiles in place.

Thus it will be seen that a very effective roof in the nature of a tile roof, but more

or less of a composite roof, will be provided, the upper surface consisting of tile while below it other materials of less weight and expense are also employed. The amount of tile is thus reduced as compared to the ordinary tile roof and consequently weight and expense is reduced. At the same time the roof is highly efficient, fireproof and waterproof, and gives satisfactory results.

If desired small metal strips 7 can be employed, the same being laid underneath the tile at the joints 8 between successive tiles so as to provide an added protection.

In Fig. 2 I show an ordinary shingle roof reconstructed so as to be in the nature of a tile roof involving my present invention. In this arrangement the usual roof timbers 1 are shown and upon them are secured the shingles 10—10. Upon these shingles 10 are mounted the strips or layers 4 of felt or similar material in the manner just described in connection with the construction of Fig. 1. Upon these strips 4 are mounted the tiles 5 in accordance with the preceding arrangement and fastened in position by nails 6. Thus the shingle roof will be covered by the tiles and the whole will in effect form a composite roof in the nature of a tile roof with all the advantages of a tile roof as compared to a shingle roof.

In place of the tiles 5 other material of a more or less similar nature may be employed and the construction of the composite supporting structure underlying the tiles may be varied.

It will be understood that other changes and modifications may be made without departing from the spirit of the invention.

What I claim as my invention is:

1. A roof construction having a plurality of rows of tile mounted one above the other and layers of felt below said tile, there being two layers of felt below each row of tile, the upper layer of felt for one row of tile extending upwardly and forming the lower layer of felt for the row or tile next above.

2. A roof construction comprising supporting members and wooden strips mounted one above another with the lower edges of each strip being fitted over the upper edge of the strip next below, layers of felt mounted upon said strips and rows of tile mounted on said felt, said rows of tile corresponding substantially with said strips, and there being two layers of felt

- between each strip and the row of tile mounted thereon, the lower layer of felt for each strip being extended downwardly and comprising the upper layer of felt for the 5 row of tile next below.
3. A roof comprising roof timbers, cross strips mounted thereon and overlapping one another, felt strips mounted upon said cross strips and overlapping the upper portions 10 of the strips respectively next below them, and overlapping tiles mounted and secured in position above said felt strips, the overlapping portion of said felt strips extending down between the overlapping tiles.
- 15 4. A covering for a shingle roof consisting of overlapping felt and tile, there being a strip of felt and a row of tile corresponding to each row of shingles, said felt being positioned between the shingles and tiles so 20 that the portion of the shingles usually exposed has two layers of felt thereon and the overlapping sections of tile are separated by a single layer of felt.
5. A roof comprising a shingle roof covered with overlapping strips of felt and rows of tile so arranged that there are two 25 layers of felt between the exposed surface of the shingles and the tile, and a single layer of felt between the overlapping portions of the tile.
6. A roof comprising an underlying supporting structure composed of a plurality of overlapping members and a covering for said supporting structure comprising over- 30
- lapping strips of felt and rows of tile, there 35 being a strip of felt and a row of tile corresponding to each row of said overlapping members, the felt being positioned between the supporting members and tiles so that the upper exposed surface of the supporting 40 members has two layers of felt thereon and the overlapping sections of the tiles are separated by a single layer of felt.
7. In a roof construction, a supporting structure comprising a plurality of overlapping shingles, a plurality of strips of waterproofing material each extending over at least two of said shingles, the adjacent 45 strips of waterproofing material having portions in superposed relation to afford two 50 layers over each shingle, and a plurality of tiles arranged one on each of said superposed layers.
8. In a roof construction, a supporting structure comprising a plurality of overlapping shingles, a plurality of strips of waterproofing material each extending over at least two of said shingles, the adjacent 55 strips of waterproofing material having portions in superposed relation to afford two 60 layers over each shingle, a plurality of tile sections arranged one on each of said layers having at least one margin thereof overlying the margin of an adjacent tile section.
- In witness whereof, I hereunto subscribe 65 my name this 30th day of April, A. D. 1919.

GEORGE R. DEAN.
